Patented Jan. 15, 1918.

UNITED STATES PATENT OFFICE.

MATTHEW L. KING, OF BRADLEY, ILLINOIS.

FORM FOR MASONRY STRUCTURES.

1,253,981.

Specification of Letters Patent. Patented Jan. 15, 1918.

Application filed January 27, 1913, Serial No. 744,576. Renewed June 20, 1917. Serial No. 175,972.

To all whom it may concern:

Be it known that I, MATTHEW L. KING, a citizen of the United States, residing at Bradley, in the county of Kankakee and 5 State of Illinois, have invented certain new and useful Improvements in Forms for Masonry Structures, of which the following is a specification.

The object of my invention is to provide 10 a form of simple, durable and inexpensive construction for use in building frames out of plastic material for openings in buildings.

More particularly, it is my object to provide 15 a form for building the door frame and jambs for a continuous opening in a silo wall, in which form door sections or form members of the same size are employed, thereby enabling me to build a frame which 20 exactly fits the silo door sections.

My invention consists in the construction, combination and arrangement of the various parts of the device whereby the objects contemplated are attained, as hereinafter more 25 fully set forth, pointed out in my claims and illustrated in the accompanying drawings, in which—

Figure 1 shows a side elevation of a portion 30 of a silo wall showing the door opening with my form installed in position.

Fig. 2 shows a horizontal, sectional view taken on the line 2—2 of Fig. 1.

Fig. 3 shows a detail, horizontal, sectional view of portions of my improved form for 35 masonry structures.

Fig. 4 shows a detail view of a retaining rod, and

Fig. 5 shows an end view of one side of 40 my improved form for masonry structures without showing the silo or other wall.

In the accompanying drawings, I have used the reference numeral 10 to indicate generally the wall of a building, such as a silo or other structure, which wall is preferably provided with a continuous door opening 45 11. My form is designed particularly for forming jambs or frames for said door openings which jambs or frames are built to exactly fit door sections of certain sizes.

50 My form is composed of the adjacent wall member 10 which may be in the form of wooden stave, cement block, hollow tile or other material. It will be understood that where a hollow block or tile is used, a small

amount of the cement will flow into the 55 block or tile. This has the advantage of firmly securing the jamb member which is made of plastic material to the wall.

I employ upright, outer members 12, preferably made of somewhat resilient material, 60 the main body of which is curved in cross section, as shown in Figs. 2 and 3, to correspond with the curve of the outside of a silo wall. At their adjacent edges, the members 12 are extended inwardly with a sharp 65 curve at 14 and then have portions 13 extending toward each other in a plane substantially at right angles to the planes of the portions 14, it being my purpose to form on the outside of the door jambs adjacent 70 curves 15 for receiving fastening devices on doors. The ends of the form members 12 adjacent to the door opening, I shall call the inner ends. Extending from the inner ends of the portions 13 inwardly and away from 75 each other are flat vertical metal form members 16 having portions 17 extending into the open space between the member 16 and the structure wall, for reinforcing purposes. The members 16 and the portions 17 may be 80 ordinary T irons. The members 16 are designed to form a part of the form and also to remain as a permanent part of the door jamb and the outer faces of the member 16 are designed to fit the beveled edge of the 85 door. On the inside of the structure, I provide vertical form members 17^a of approximately the same length as the members 12 and designed to constitute the inner wall of the form. The form members 17^a are of 90 sufficient width to overlap the inner part of the wall 10 and extend beyond the members 16 into the door opening. The members 17^a may be slightly beveled to fit the other form members hereinafter described. 95

For properly spacing the members 16 apart, I employ a form member 18, which may be an ordinary door section or a form member of substantially the same shape and size. By using the form member 18 of the same 100 shape and size of the door section, I am enabled to space the members 16 apart exactly the proper distance for receiving the door sections when the jamb is completed by the use of my improved form. For holding the inner edges of the form members 16 against spreading, I employ a rod or bar 19 having at its ends hook members 20 designed to en-

gage the inner edges of the form members 16, as shown in Figs. 1, 2 and 3. The rod or bar 19 is preferably somewhat longer than the ordinary distance between the inner edges of the members 16 so that if the form member 18 should vary somewhat in width, the rod 19 may be arranged at an acute angle with relation to the longitudinal axis of the door opening, as shown in Fig. 1 and will 10 still hold the members 16 against spreading.

I preferably secure to the portion 17 of the members 16, a plurality of anchoring devices 21 designed to extend through the masonry door jamb to and into the structure 15 wall 10. In order to further prevent the spreading of the members 16 and to hold them in their proper position, I provide rods 22 having at their ends hook members 23 designed to engage the members 17, as 20 shown in Fig. 2. The rods 22 are designed to be secured just above and just below the form members 12 and against the edges of the member 16 opposite the edges to which the hook members 20 of the rods 19 are 25 secured. For holding the form members 12 and 17^a in position, I have provided the following means.

Near each end of the members 12, outside the door opening, I provide a pair of angle 30 irons 24 having one portion in a horizontal plane, and extending outwardly from the form members 12 and having the other portion in a vertical plane and resting against the form members 12. In the vertical member 35 of the angle irons 24 I provide two longitudinally elongated slots 25 designed to be adjacent to the members 12 when the parts are installed in position. The members 17^a and 12 are provided with suitable openings 40 which register with each other on each side of the door opening, and extending through the members 17^a and 12, and through the opening 25, at each end of the angle bar, is a bolt or rod 26, the outer end of which is 45 screw threaded at 27. On the outer end of each rod 26 is a thumb nut 28. On the rod 26, between the thumb nut 28 and the angle bar 24, I provide suitable collars 29 and washers 30. On account of the fact that the 50 thickness of the wall 10 may vary in different silos, the slots 25 are elongated so that the bolts or rods 26 will be received in said slots in all cases. For holding and supporting the members 12 in position, I provide bars 30^a, the inner ends of which are 55 designed to rest against the outer surfaces of the portions 13 of the form members 12. The bars 30^a extend outwardly from the structure wall, adjacent to the horizontal 60 flanges of the angle bar 24. The bars 30^a are provided with elongated slots 31 and the horizontal flanges of the angle bar 24 are provided with suitable openings in which are received bolts 32 which extend through 65 the slots 31 and are formed with screw

threaded ends on which are winged thumb nuts 33. It will thus be seen that on account of the elongated slots 31, the bars 30^a are adjustable for use with silo walls of varying thicknesses.

In installing my improved form for masonry structures for building the jambs or frames of silo or other doors, the members 17^a and 12 are placed in horizontal position. The member 12 is of somewhat resilient material so that it may be bent or sprung to conform to the shape of the structure wall regardless of the thickness of the wall 10. The members 16 are placed in upright position and the anchoring or reinforcing devices 21 are secured thereto. The rods 19 are secured in position and the rods 22 mounted in their proper places. I then install the bars 24 and place the bolts 26 in the proper opening. The bars 30^a are then secured in position 80 and the door 18 is placed between the members 16. On the outer surface of the form member 18 I secure sliding catch members 35, mounted in guide ways 36 which may be of ordinary construction. The catch 90 members 30^a are preferably mounted in position slightly spaced apart from the member 18, so that when the members are installed in position for use, the catch members 35 may be moved to engage the outer 95 surfaces of the portions 13 of the form member 12, as shown in Fig. 3. If desired, suitable form members may be placed in position for leaving an air space in the plastic material. When the form members 100 are in position at the bottom of the door opening 37, plastic material is poured from the top into the space between the members 12 and 17^a, the wall and the member 16. The form members, excepting the members 105 16, the reinforcing rods 21 and the rods 22 are designed to be removed when the plastic material is hardened.

The advantages of my improved form may be seen from the foregoing description. Especially, in the building of silo door frames, where it is desirable to have a door made in sections and to have said sections fit very snugly to make an air tight joint, it is very difficult to build a frame which the door sections will fit against properly. By using my improved form and employing as one of the members thereof, the member 18, made in the shape and form of a door section, the door jamb or frame, when completed, will 110 exactly fit the door sections to be used in the door opening. By using the members 16 having smooth faces, inclined in the positions shown in Figs. 2 and 3 in connection with the member 18, I am able to form a 115 frame having a smooth inclined face suitable to fit the door section, which, especially in silos is installed from the inside. On account of the position of the members 16, the door section will be pressed more tightly to 120 125 130 135

position by any pressure from the ensilage within the structure.

I claim as my invention:

1. A form comprising upright T bars, an upright member engaging one flange of each T bar, means for holding the T bars against spreading, a form member between the T bars for holding them apart, an upright form member spaced from the respective 10 first named upright members on the opposite side of each T bar, and provided with shoulders at their adjacent edges, bars adjustably secured to said upright members, and adjustable means mounted on said bars 15 for engaging said shoulders.

2. In a form for frames for openings in buildings, upright T bars arranged with their adjacent faces in intersecting vertical planes to form a beveled door opening, rods 20 having at their ends hook members for engaging the adjacent edges of the T bars, similar bars for engaging the shank flanges of the T bars, an upright form member for the inner faces of the frame on one side of 25 each T bar, an upright form member for the outer faces of the frame on the other side of each T bar, said last named upright members having shoulders at their adjacent edges, bars, means for adjustably securing 30 each bar to the upright members, and means for adjustably bracing said bars against said shoulders.

3. In a device of the class described, outer upright form members curved in cross section to conform to the shape of a curved wall, having at one end an inward extension and formed on the end thereof an extension at right angles to said inward extension, said 35 form member being made of somewhat resilient material, inner form members, spaced from said outer members, upright form members between said inner and outer form members, forming a beveled door opening, bars adjustably secured to said upright form 40 members, and means for holding said beveled door opening form members against movement toward or from each other.

4. A form for frames for openings in buildings, comprising a pair of upright inner form members designed to be placed on the inside of the building on each side of the opening and to overlap the walls of the building, a pair of upright outer form members 50 designed to be placed on the outer side of the building on each side of the opening therein and to overlap the walls of the building, said last named form members having at their adjacent ends inward extensions on the ends of which are opposite extensions at 55 right angles to said inward extensions, said form members being provided with openings to receive bolts, an angle bar having one flange in a horizontal plane and the other flange in a vertical plane, said vertical flange 60 being provided with elongated slots, bolts re-

ceived in said openings in said first two named form members and in said slots, bars provided with elongated slots, said bars being designed to rest against the adjacent ends of said second form members and against 70 said horizontal flange and bolts received in said horizontal flange and in the slots in said last named bars, a form member designed to extend across the door openings, having the form and size of a door section, and means 75 for holding said last named form member in position.

5. A form for frames for openings in buildings, comprising a pair of upright inner form members designed to be placed on the inside of the building on each side of the opening and to overlap the walls of the building, a pair of upright outer form members 80 designed to be placed on the outer side of the building on each side of the opening 85 therein and to overlap the walls of the building, said last named form members having at their adjacent ends inward extensions on the ends of which are opposite extensions at right angles to said inward extensions, 90 said form members being provided with openings to receive the bolts, an angle bar having one flange in a horizontal plane and the other flange in a vertical plane, said vertical flange being provided with elongated slots, bolts received in said openings 95 in said first two named form members and in said slots, bars provided with elongated slots, said bars being designed to rest against the adjacent ends of said second form members and against said horizontal flange, bolts received in said horizontal flange and in the slots in said last named bars, a form member 100 designed to extend across the door openings, having the form and size of a door section, means for holding said last named form member in position and form members designed to remain a permanent part of the structure, having inclined faces adjacent to the edges of said door shaped form member. 110

6. A form comprising spaced upright form members, upright members each being adjacent to part of one of said first form members, means for holding said first form members against spreading, removable means 115 for holding said first form members apart, adapted to serve as a form member and as a closure device, upright members spaced from the respective second described form members adjacent to parts of the respective 120 first form members, provided with opposite shoulders.

7. A form comprising spaced upright form members, upright members each being adjacent to part of one of said first form members, means for holding said first form members against spreading, removable means for holding said first form members apart, adapted to serve as a form member and as a closure device, upright members spaced 125 130

from the respective second described form members adjacent to parts of the respective first form members, provided with opposite shoulders, and bars secured to said last described form members having means for engaging said shoulders.

8. A form comprising spaced upright form members, upright members each being adjacent to part of one of said first form members, means for holding said first form members against spreading, removable means for holding said first form members apart, adapted to serve as a form member and as a closure device, upright members spaced from the respective second described form members adjacent to parts of the respective first form members, provided with opposite shoulders, and bars secured to said last described form members having means for engaging said shoulders, said last named means being adjustable on said bars.

9. A form comprising spaced upright form members, upright members each being adjacent to part of one of said first form members, means for holding said first form members against spreading, removable means for holding said first form members apart, adapted to serve as a form member and as a closure device, upright members spaced from the respective second described form members adjacent to parts of the respective first form members, provided with opposite shoulders, bars secured to said last described form members having means for engaging said shoulders, and means for securing each of said second form members to one of said

last described form members and to said bars.

10. In a form for frames for structure openings, spaced upright form members having adjacent beveled faces and upright inner form members adjacent to one side of each first form member, an upright outer form member adjacent to one side of each first form member, means for preventing the spreading of said first form members, a form member for engaging the beveled faces of said first form members and adapted to serve as a form member for holding said beveled faces apart, and also as a door, means for engaging said outer upright members and preventing their separating, and means for connecting the respective outer upright members with the respective inner upright members.

11. A form comprising spaced upright form members, upright members each adjacent to part of one of said first form members, spaced upright members spaced from said respective second described form members each adjacent to part of one of said first form members, means for holding said first form members against spreading and removable means for holding said first form members apart a predetermined distance.

Des Moines, Iowa, December 16, 1912.
